UNITED STATES PATENT OFFICE

2,243,962

STOKER

Paul A. Ketchpel, West Englewood, N. J., assignor
to The Standard Stoker Company, Inc., a cor-
poration of Delaware

Original application August 2, 1934, Serial No.
738,039. Divided and this application January
30, 1936, Serial No. 61,518. Renewed Septem-
ber 29, 1939

21 Claims. (Cl. 110—165)

This application is a division of my co-pending application, Serial No. 738,039, filed August 2, 1934, for Stoker.

My invention relates generally to automatic furnaces, and more particularly to small furnaces such as are employed in the heating of dwellings, apartment houses and greenhouses.

One object of my invention resides in the provision, in furnaces of the type described, of a novel grate shaking arrangement.

Another object of my invention resides in the novel construction and arrangement of means for removing the ash from furnaces of the type described.

Still another object of my invention resides in the provision in furnaces of the type described, of an improved and novel combination and arrangement of stoking, grate shaking and ash removal means, that is simple in construction, cheap to manufacture, and highly efficient in operation.

To the above and other ends the invention consists in the arrangement of parts and in their relation and association one with the other or in combination as hereinafter described and as illustrated in the accompanying drawings, in which,

Fig. 1 is a vertical sectional view of a furnace room showing a furnace and stoker therefor in elevation with parts broken away and with the novel grate shaking arrangement and ash removing device shown applied thereto;

Fig. 2 is a view of the furnace in central vertical section with the stoker, grate shaker and ash removing device applied thereto and shown partly in elevation and partly in section;

Fig. 3 is a sectional plan view through the furnace and bin with the stoker shown in elevation;

Fig. 4 is a vertical central section through the lower portion of the furnace with a modified form of ash conveyor applied thereto and shown in similar section; and

Fig. 5 is a sectional view on the line 5—5 of Fig. 4.

Referring now to Figs. 1 to 3, inclusive, of the drawings, which illustrate one embodiment of the invention, a furnace room is designated by the numeral 10 and its floor is shown at 12. A furnace is shown at 13, and at 14 is the bin containing the supply of fuel for the furnace. The furnace 13 includes a firebox 15, provided with grate bars 16 forming an ash chamber 38 therebeneath, and a firing opening 17 in the furnace front wall 18 provided with a door 19. The door

19 is arranged to permit manual and stoker firing through the firing opening 17.

It will be understood as the description proceeds that the invention is not limited to the particular relation of the bin 14 and the furnace 13 illustrated, since the bin may occupy any one of a number of positions around the furnace and may be nearer to it or farther away. As shown, the bin 14 is at one side of the furnace 13 and a stoker elevating conduit 20 extends upwardly and laterally from a position near the bottom of the bin 14 through the bin wall 21 and terminates a short distance above the firing opening 17 of the furnace 13. A screw conveyor 26 is mounted in the elevating conduit 20 and is arranged to be driven from its upper end through the drive shaft 29. The conduit 40 communicates with the upper end of the elevating conduit 20 and curves downwardly toward the firing opening 17. At its lower end the conduit 40 communicates with a chute 42, that curves downwardly and communicates with the firing opening 17 through the opening 43 in the door 19, discharging fuel into the furnace. The details of construction of the stoker are not described here since they form the basis of my application Serial No. 738,039, of which the present application is a division.

In order to prevent the accumulation of ashes on the grates below the fuel bed, which would hinder the natural draft from passing through the fuel bed, a novel grate shaking arrangement is provided. The lower end of the shaft of the screw conveyor 26 extends into the compartment 39 and is connected with the speed reducer 55 by the universal joint 56. Movement is transmitted from the speed reducer 55 to the drive shaft 57 through the universal joint 58. The drive shaft 57 extends forwardly from the speed reducer through a housing 59, which extends beneath the floor of the fuel bin, to the furnace 13 and is connected at its forward end to the shaft 60 by a universal connection 61.

The stoker conveyor screw 26 and the shaft 45 57 are angularly related both in a vertical plane as shown in Fig. 1 and in a horizontal plane as shown in Fig. 3. In order to reduce the angularity, considered in a vertical plane, at the universal joint 58 between the shaft of the conveyor screw 26 and the shaft of the speed reducer 55, the speed reducer is mounted at an angle to the horizontal, as shown in Fig. 1. To obtain the most favorable angle, considered in a horizontal plane, at the universal joints 56 and 58 between 50 the shaft of the conveyor screw 26 and the shaft

57 with the shafts of the speed reducer, the speed reducer is located so that the angle between the shaft 57 and the speed reducer shaft to which it is connected is approximately equal to the angle between the shaft of the conveyor screw 26 and the speed reducer shaft to which it is connected.

The shaft 60 is mounted in a bearing 62 formed in the plate member 63 and carries an eccentric 64. As the shaft 60 rotates, the eccentric alternately engages the legs 65 and 66, which are a part of the bifurcated extension 66a, rigidly attached with the grate shaker bar 67 by bolts 124 or equivalent means, thereby giving the grates an oscillating motion. A handle 68 is provided for manually shaking the grate 16 independently of the stoker mechanism if it is necessary at any time to fire the furnace manually. To permit of adjustment of the amount that the eccentric 64 rocks the grate 16, a link 69 is provided connecting the legs 65 and 66, which has holes 70 of varied spacing to adjust the lost motion between the eccentric 64 and the legs 65 and 66. The lost motion between the eccentric 64 and the legs 65 and 66 permits the grate to remain stationary for a period of time at each of the limits of its oscillation. Since the grates remain in rocked position for a space of time, the amount of air drawn up through the grates is increased. This is of particular importance when the openings between the grates are restricted as in installations adapted for burning of fuel of small size. It is evident that the air supply to the firebox may be increased or decreased by increasing or decreasing the lost motion between the eccentric 64 and the legs 65 and 66. A protecting shield or plate 71 may be attached to the legs 65 and 66 to prevent ashes from dropping on the eccentric 64 and from getting in the bearing 62.

The rate at which the grates are oscillated is determined by the rate of speed of the stoker conveyor screw 26, since they are operatively connected therewith through the shafts 60 and 57 and speed reducer 55. Thus, if the stoker is speeded up to produce heavier firing, the grates are oscillated more rapidly to take care of the greater amount of ash formed.

A conduit including the trough-like portion 12 and the tubular portion 78 is mounted beneath the grate 16 to receive the ashes falling therethrough and extends to the compartment 85. A slope sheet 73 fixed to the rear wall of the furnace in the ash pit 38 beneath the grate 16 and another sheet 75 secured to the ash door 78 provide a self-cleaning arrangement in the ash pit 38 permitting the ash to drop into the trough 72. The slope sheets 73 and 75 permit the use of a trough, the open mouth portion of which is considerably smaller in area than the grate area, while receiving all the ash passing through the grate.

The ashes are conveyed from the trough 72 by the screw conveyor 71 through the conduit 78 and allowed to drop through the outlets 79 and 80 into the ash containers 81 and 82. The ash containers are provided with dust proof lids 83 and 84 closely and telescopically fitting the outlets 79 and 80. To keep the ash containers out of sight and provide more floor space, they are disposed in the compartment 85 beneath the furnace room floor, this compartment being covered by the door 85a.

In Figs. 4 and 5 is shown a modified form of the ash removing device, wherein means is pro-

vided for stopping the ash conveyor 86 after the ash receptacles have become filled, allowing the ashes to accumulate in the trough 87 and ash pit 88. The ash conveyor conduit 89 has a hinged door or end cover 91 that is pushed open by the accumulation of ashes in the conduit 89 when the ash receptacles are filled. Opening of the door 91 moves a catch 92 and releases the latch 93 mounted on the same shaft as the bell crank 94, which by reason of the weight 95 swings downward moving the rod 96 toward the left.

The rod 96 is connected with the lower end of a clutch yoke 97 which is pivotally mounted at 125 in a bracket 98 attached to the end plate 99. The yoke 97 engages the clutch member 100 which is slidably keyed on the shaft 101. Normally the clutch member 100 is in engagement with a companion clutch member 102 universally connected with and driven by the shaft 103; however, when the accumulation of ash at the end of the conduit 89 opens the door 91 releasing the latch 93 and causing the bell crank 94 to move the shaft 96 to the left, the clutch members 100 and 102 are disengaged, as shown in Fig. 4, and operation of the ash conveyor screw 96 is stopped.

An alarm may be provided for indicating when the clutch members 100 and 102 have become disengaged and have thereby interrupted the operation of the ash conveyor 86. A clapper 114 is pivotally attached at one end to the clutch member 102, as at 126, and rotates therewith. Looking at Fig. 5, the clutch member 102 rotates in a counterclockwise direction and the clapper 114, during the ascending portion of its movement, because of its pivotal connection 126, rests against the hub portion of the clutch member 102. During the descending portion of its movement the clapper 114 becomes overbalanced and swings downwardly about its pivotal connection 126 striking the bell 115. The bell 115 is mounted on the yoke 97 below the pivotal connection 125 and moves into the path of the clapper 114 when the yoke is moved by the rod 96 in a direction to shift the clutch member 100 out of engagement with the clutch member 102.

From the foregoing description it will be apparent that the novel combination and arrangement of parts together with the particular structure of various elements permits the maintenance of a shallow level fuel bed that is continuously being replenished. The fuel feeding portion of my automatic furnace is arranged to spread fuel over the furnace grate continuously in a thin even stream; the grate shaking portion, since its operation is synchronized with the stoker, shakes the ashes from the fire as rapidly as the fuel is consumed; and, the ash removing portion continuously conveys the ashes away. As a result, a thin even fire, free from ashes, may be constantly maintained.

A shallow fire burns at a much higher temperature and more nearly resembles gas and oil fires, because the natural draft of the chimney can cause the air to pass up through the fire bed and produce a more nearly perfect combustion of the fuel than is possible with a deep fire and a forced draft. Also an increase in the useful heating surface of the furnace is gained over those types of stokers that carry a deep fire bed, since in the latter the fire bed smoulders at a relatively low temperature and usually includes an accumulation of ash. Tests have also shown that the flue gases taken from a furnace having a comparatively thin and hot fire con-

tain a great deal less unburned carbon than the flue gases taken from a slow smouldering fire, such as is the condition in deep fire beds.

I claim:

1. In a furnace room having a floor, a furnace provided with a grate and an ash chamber therebeneath, a trough-like depression in said floor communicating with said ash chamber, a fuel bin, the floor of said fuel bin being on a level with said furnace room floor, a stoker including a conveyor screw arranged to convey fuel from said bin to the furnace, said conveyor screw having an extended shaft projecting beneath the level of said floor, a screw conveyor in said trough-like depression for conveying ash, a housing beneath the fuel bin floor and a drive shaft in said housing operatively connected at one end below the level of said floor with the stoker conveyor screw shaft extension and at its other end with the ash conveyor screw.

2. In a furnace room having a floor, a furnace, a trough-like depression in said floor beneath the furnace arranged to receive ash from the furnace, an ash conveyor mounted in said depression, a fuel bin, the floor of said fuel bin being on a level with said furnace room floor, a stoker including a conveyor screw arranged to convey fuel from said bin to the furnace, a compartment beneath the fuel bin floor, the shaft of said stoker conveyor screw extending into said compartment, a housing beneath the fuel bin floor communicating at one end with said compartment and at the other end with said trough-like depression, a drive shaft in said housing for said ash conveyor and gearing in said compartment operatively connecting said stoker screw conveyor shaft and said drive shaft.

3. In a furnace, a grate provided with a grate shaker bar, an ash pit beneath said grate, means including a screw conveyor for conveying ashes from said pit, a yoke rigidly secured to said grate shaker bar, said yoke having a pair of leg members extending downwardly, one on each side of the axis of said screw conveyor, an eccentric mounted to rotate with said screw conveyor and arranged to alternately engage said leg members for rocking said grates first in one direction and then in the opposite direction.

4. In a furnace, a grate provided with a grate shaker bar, an ash pit beneath said grate, means including a screw conveyor for conveying ashes from said pit, a yoke rigidly secured to said grate shaker bar, said yoke having a pair of leg members extending downwardly, one on each side of the axis of said screw conveyor, an eccentric mounted to rotate with said screw conveyor and arranged to alternately engage said leg members for rocking said grates first in one direction and then in the opposite direction, said leg members being spaced such a distance apart that the eccentric will intermittently engage said leg members.

5. In a furnace room having a floor, a furnace and a fuel bin, a firing opening in said furnace, a stoker fuel conveyor extending upwardly from the bottom of said bin to the firing opening in said furnace, a compartment beneath the floor of said fuel bin, said fuel conveyor having a shaft extending through the floor of said bin into said compartment, an ash conveyor beneath said furnace, said ash conveyor having a shaft extending into said compartment, a speed reducer in said compartment having a shaft universally connected with said stoker conveyor shaft and a second shaft universally connected with said

ash conveyor shaft, said speed reducer being mounted at such an angle that the angle between its first named shaft and the stoker conveyor shaft is approximately equal to the angle between its second named shaft and the ash conveyor shaft.

6. In a furnace, a grate, an ash chamber beneath said grate, a trough arranged to receive the ashes from said chamber, a conveyor in said trough, mechanism associated with said conveyor for shaking said grate, the cross sectional area of said trough at its open mouth being less than the cross sectional area of said chamber, and a plurality of upstanding plates mounted in said chamber forming a restricted opening in the lower portion of said chamber, one of said upstanding plates forming a shield for said grate shaking mechanism from the ash dropping from said grate.

7. In combination with a furnace having a grate, a stoker including a fuel conveyor having a fuel receiving end in communication with a source of fuel supply and a fuel delivery end adjacent the furnace, means for operating said fuel conveyor from its end adjacent the furnace, an ash conveyor beneath said grate for removing ashes from the furnace, means operatively connecting said ash conveyor with the fuel receiving end of said fuel conveyor for operating the ash conveyor from the fuel conveyor, means operatively connected with said ash conveyor for shaking said grate, and means for rendering said grate shaking means and said ash conveyor inoperative independently of said fuel conveyor.

8. In a furnace, a grate provided with a grate shaker bar, an ash pit beneath said grate, means for conveying ashes from said pit, a rotatably mounted eccentric, a common actuator for said ash conveyor and eccentric, and means operatively connected to said grate shaker bar arranged to be engaged by said eccentric for rocking said grates first in one direction and then in the opposite direction.

9. In combination with a furnace having a firing opening and a grate, a stoker fuel conveyor leading from a source of fuel supply to the firing opening in said furnace, an ash conveyor beneath said grate, said fuel conveyor and said ash conveyor each having shaft extensions terminating adjacent each other, power transmission means operatively connecting the adjacent ends of said shafts, said transmission means having a shaft universally connected with said stoker conveyor shaft and a second shaft universally connected with said ash conveyor shaft, said transmission means being mounted so that the angle between its first named shaft and the stoker conveyor shaft is approximately equal to the angle between its second named shaft and the ash conveyor shaft.

10. In combination with a furnace having a grate, a stoker for conveying fuel from a source of supply to the furnace and delivering it onto said grate, an ash pit beneath said grate, an ash receptacle, means for conveying the ashes from said pit to said ash receptacle, means for operating said stoker, a drive connection between said stoker and said ash conveyor for operating the latter, means operatively associated with said ash conveyor for shaking said grate, and means for automatically rendering both said ash conveyor and said grate shaking means inoperative when said receptacle is filled, without interrupting operation of said stoker.

11. In combination with a furnace having a

grate, a stoker for conveying fuel from a source of supply to the furnace and delivering it onto said grate, an ash pit beneath said grate, an ash receptacle, means for conveying the ashes from said pit to said ash receptacle, means for operating said stoker, a drive connection between said stoker and said ash conveyor for operating the latter from said stoker, and means for automatically rendering said ash conveyor inoperative when said receptacle is filled, without interrupting operation of said stoker.

12. In combination with a furnace having a grate, a stoker for conveying fuel from a source of supply to the furnace and delivering it onto said grate, an ash pit beneath said grate, conveying means for removing ashes from said pit, means for operating said stoker, a drive connection between said stoker and said ash conveyor for operating the latter, said drive connection including a clutch, and means responsive to an accumulation of ash arranged to disengage said clutch for rendering said ash conveyor inoperative without interrupting operation of said stoker.

13. In a furnace, a grate provided with a grate shaker bar, an ash pit beneath said grate, conveying means for removing ashes from said pit, means securely attached to said grate shaker bar including a pair of depending members, one on each side of said conveying means, an eccentric mounted to rotate with said conveying means and arranged to alternately engage said depending members for rocking said grates first in one direction and then in the opposite direction.

14. In a furnace, a grate provided with a grate shaker bar, an ash pit beneath said grate, conveying means for removing ashes from said pit, means attached to said grate shaker bar including a pair of depending members, one on each side of said conveying means, an eccentric mounted to rotate with said conveying means and arranged to alternately engage said depending members for rocking said grates first in one direction and then in the opposite direction, said depending members being mounted for adjustment a desired distance from said eccentric for varying the rocking movement of said grates.

15. In combination, a furnace having a firing opening in an upright wall thereof, a fuel bin at one side of said furnace, a stoker conduit including a fuel conveyor extending downwardly and laterally with respect to said furnace from said firing opening to the bottom of said fuel bin, an ash conveyor extending laterally with respect to the furnace from the lower portion of the furnace to a point remote therefrom, said fuel conveyor and said ash conveyor each having shaft extensions terminating adjacent each other, means operatively connecting the adjacent ends of said shafts including speed reducing means for operating said ash conveyor at a slower speed than said fuel conveyor, and means operatively connected with the upper end of said fuel con-

veyor for actuating said fuel conveyor and said ash conveyor.

16. In combination with a furnace having a grate, a stoker fuel conveyor delivering fuel from a source of fuel supply to the furnace, means for operating said stoker conveyor, an ash conveyor beneath said grate for removing ashes from the furnace, means operatively connecting said ash conveyor with said stoker conveyor for operating the ash conveyor from the stoker conveyor, and means for rendering said ash conveyor inoperative independently of said stoker conveyor.

17. In combination with a furnace having a grate, a stoker fuel conveyor delivering fuel from a source of fuel supply to the furnace, means for operating said stoker conveyor, an ash conveyor beneath said grate for removing ashes from the furnace, means operatively connecting said ash conveyor with said stoker conveyor for operating the ash conveyor from the stoker conveyor, means operatively connected with said ash conveyor for shaking said grate, and means for rendering said grate shaking means and said ash conveyor inoperative independently of said stoker conveyor.

18. In combination with a furnace having a grate, a stoker fuel conveyor delivering fuel from a source of fuel supply to the furnace, means for operating said stoker conveyor, means for shaking said grate, means operatively connecting said grate shaking means with said stoker conveyor for operating the grate shaking means from the stoker conveyor, and means for rendering said grate shaking means inoperative independently of said stoker conveyor.

19. In a furnace, a grate, an ash compartment beneath said grate, means for conveying ashes from said compartment, a rotatably mounted cam, a common actuator for said ash conveyor and means operatively connected to said grate and engaged by said cam for moving said grate first in one direction and then in the opposite direction.

20. In a furnace, a grate, an ash compartment beneath said grate, conveying means for removing ashes from said compartment, said grate being provided with a pair of depending members, one on each side of said conveying means, and means operatively associated with said conveying means arranged to alternately engage said depending members for rocking said grates first in one direction and then in the opposite direction.

21. In a furnace, a grate, an ash compartment beneath said grate, conveying means for removing ashes from said compartment, means securely attached to said grate including a pair of depending members, one on each side of said conveying means, means mounted to rotate with said conveying means arranged to alternately engage said depending members for rocking said grate first in one direction and then in the opposite direction.

PAUL A. KETCHPEL.
